UNITED STATES PATENT OFFICE.

THOMAS F. BUCKLEY, OF SCRANTON, PENNSYLVANIA.

SPRING-FORMING MACHINE.

Application filed July 30, 1921. Serial No. 488,545.

To all whom it may concern:

Be it known that I, THOMAS F. BUCKLEY, of Scranton, in the county of Lackawanna and State of Pennsylvania, have invented a certain new and useful Improvement in Spring-Forming Machines, of which improvement the following is a specification.

My present invention relates to spring forming machines of the general class or type of that set forth in Letters Patent of the United States No. 1,275,377, granted and issued to myself and Samuel S. Riegel, under date of August 13, 1918, and its object is to provide an appliance of such type which shall be of simplified construction and reduced cost, and which shall embody improved facilities for desired adjustment.

The improvement claimed is hereinafter fully set forth.

20 In the accompanying drawings: Figure 1 is a plan or top view, partly in section, of a spring forming machine, illustrating an embodiment of my invention; Fig. 2, a side view, in elevation; Fig. 3, an end view, as seen from the right; Fig. 4, a side view of the cross head, illustrating a structural modification of the operating means; Fig. 5, an end view of the same; and, Fig. 6, a plan view, on a reduced scale, of the table, showing a disposition adapted for making springs of special curvature.

In the practice of my invention, referring descriptively to the specific embodiment thereof which is herein exemplified, I provide a flat table or plate, 1, of stout metal, which is supported on vertical standards, 1^a, adjacent to its ends. A fluid pressure cylinder, 2, is fixed horizontally on a bracket, 2^a, which projects from the front 40 of the table, at the middle thereof, and is firmly fixed thereto. The cylinder, 2, is fitted with a properly packed piston, 2^c, which is secured upon a piston rod, 2^d, projecting from the inner end of the cylinder, and operating fluid, which is preferably compressed air, is supplied to actuate the piston, the admission and exhaust being controlled by any suitable known valve mechanism, which does not, in and of itself, form 50 part of my invention, and is not, therefore, herein illustrated.

A cross head, 3, is secured to the outer end of the piston rod, said cross head being coupled, by a plurality of connections, to a 55 curved templet or formation plate, 6. In the instance exemplified, a middle and two

end connections are applied, each of said connections comprising two rods, 4, having right and left hand screw threads, respectively, and connected by a correspondingly threaded nut or turnbuckle, 5, the opposite ends of the rods being secured to the cross head and the formation plate, respectively. By this means, the curvature of the formation plate may be readily adjusted as desired.

A fixed flexible resistance member, which is shown in the form of a flat link chain, 7, the depth of which is substantially equal to the width of the widest spring plates 70 which are to be bent, is extended longitudinally on the table, 1. The resistance member is held in tension by two helical springs, 8, located below the table, each of said springs being coiled on a rod, 8^a, which is 75 coupled to a block, 7^a, fitted to slide in a guide slot, 1^c, in the table, and bolted to one end of the resistance member, 7. The springs, 8, bear, at one end, on collars, 8^b, on the rods, 8^a, and, at the other end, on abutments, 8^c, fixed to the table, and their tension may be adjusted, as desired, by nuts, 8^d, engaging screw threads on the rods, 8^a.

The chain, 7, is maintained, at two points in its length, at its normal distance from the cross head, as determined by the tension to which it is subjected, by the springs, 8, and the extent of its operative flexible length is limited by the blocks, 9, which are fitted, with the capacity of longitudinal 90 movement, on the table, and are secured adjustably thereto, by bolts, 9^a, and nuts, said bolts passing through slots, 1^d, in the table, which are located at a right angle to the axial line of the piston rod, 2^d. The blocks, 9, are coupled, by bolts, 9^b, to anvil blocks, 9^c, secured to the chain, 7.

The structural modification of the construction last above described, which is shown in Fig. 6, is designed for use in the manufacture of leaf springs of special curvature. The slots, 1^d, in which the bolts connecting the blocks, 9, are adjustable, are, in this case, inclined, at equal angles, to the axial line of the piston, 2^c, instead of being 105 at a right angle thereto, as in the instance first described. It will be seen that by this disposition of the guide slots and anvil blocks, a double curvature may be imparted to the spring leaves, as clearly shown in 110 Fig. 6.

Figs. 4 and 5 illustrate means for moving

the cross head by power applied through a driving belt, which are applicable in shops where fluid pressure, for operating the piston of an operating cylinder, is not conveniently available. To this end, a shaft, 13, carrying a belt pulley, 14, is journaled in suitable bearings below the table, and cranks or discs, 15, fixed on said shaft, are coupled, by links, 16, to lugs, 3^a, on the bottom of the cross head, 3. The length of traverse imparted to the cross head by vibration of the shaft, 13, may be varied, as desired, by adjustments of the bolts, 16^a, which connect the links, 16, to the crank discs, 15, in slots, 15^a, in said crank discs.

In the operation of the machine, the formation plate, 6, having been bent to the curvature which it is desired to impart to the spring plate, said plate is heated to a proper temperature for bending, and is stood, on one of its sides, against the formation plate. Motive fluid is then admitted to the cylinder, 2, and the piston, 2^c, and connected cross head, 3, are thereby forced forwardly or towards the chain, 7, and the plate is pressed between the formation plate and the chain and bent to the desired curvature, with any initial set or extra draw that may be necessary in spring construction. The ends of the spring plate are held in proper position by the pressure of the anvil blocks, 9^c, on the chain, and the yielding of the intermediate portion of the length of the chain is determined by the curvature of the formation plate. When the plate has been bent, outwardly acting pressure is released from the piston, 2^c, and the piston and cross head are retracted to their original position. It will be seen that, by the lengthening or shortening of the working length of the chain, spring plates of any length within the capacity of the machine, may be bent to a desired curvature.

I claim as my invention and desire to secure by Letters Patent:

1. In a spring forming machine, the combination of a supporting table, provided with guide slots; a flexible resistance member, extending longitudinally thereon; blocks, connected to the ends of said member and fitted to slide in said guide slots in the table; means, located below the table and connected to said blocks, for imposing tension on the resistance member; a curved formation plate, which is movable towards and from the resistance member; and means for imparting movement to the formation plate.

2. In a spring forming machine, the combination of a supporting table, provided with guide slots; a flexible resistance member, extending longitudinally thereon; blocks, connected to the ends of said member and fitted to slide in said guide slots in the table; rods, located below the table and coupled to said

blocks; abutments, fixed to the table; abutments, fixed on the rods; springs, bearing on said abutments; a curved formation plate, which is movable towards and from the resistance member; and means for imparting movement to the formation plate.

3. In a spring forming machine, the combination of a supporting table, provided with guide slots; a flexible resistance member, extending longitudinally thereon; means for imparting tension to said resistance member; blocks, fitted to slide longitudinally on said table; adjusting bolts, connected to said blocks, and passing through said guide slots in the table; anvil blocks, connected to said first specified blocks and bearing on the resistance member; a curved formation plate, which is movable towards and from the resistance member; and means for imparting movement to the formation plate.

4. In a spring forming machine, the combination of a supporting table; a flexible resistance member, extending longitudinally thereon; means for imparting tension to said resistance member; a cross head, fitted to traverse the table, towards and from the resistance member; a curved formation plate; a plurality of adjustable connections, coupling said formation plate to the cross head; and means for imparting movement to the cross head.

5. In a spring forming machine, the combination of a supporting table; a flexible resistance member, extending longitudinally thereon; means for imparting tension to said resistance member; a cross head, fitted to traverse the table, towards and from the resistance member; a curved formation plate; a plurality of adjustable connections, coupling said formation plate to the cross head, each comprising two rods, one secured to the formation plate, and the other to the cross head, and having right and left hand screw threads, respectively, on their opposite ends, and a correspondingly threaded nut or turnbuckle, engaging said screw threads; and means for imparting movement to the cross head.

6. In a spring forming machine, the combination of a supporting table; a flexible resistance member, extending longitudinally thereon; means for imparting tension to said resistance member; a cross head, fitted to traverse the table, towards and from the resistance member; a curved formation plate, to which pressure is imparted by the cross head; a vibratable driving shaft; a belt pulley thereon; and links, coupling the cross head to cranks on the driving shaft.

THOMAS F. BUCKLEY.
